IMPULSE SENDER

Georg Zapf, Berlin-Charlottenburg, Germany, assignor to Siemens & Halske Aktiengesellschaft, Siemensstadt, near Berlin, Germany

Application May 25, 1938, Serial No. 210,042
In Germany June 15, 1937

8 Claims. (Cl. 179—90)

The subject of the invention is a numerical sender with a key strip, through whose keys a mechanical interpreting device is influenced. The invention aims at a construction of the numerical sender that will simplify and expedite operation and at the same time correct the impulse sent out.

Numerical senders with only one key strip are already known which so work that to send out several figure numbers a corresponding series of impulses is sent out for each digit through the same key strip. In this way an impulse sending switch device tests the contacts set by the keys electrically one after another so that the setting of the next figure can be immediately proceeded with, before the previously set figure is completely tested. This arrangement, however, shows a very complicated construction. With another arrangement of prior art with only one key strip either the pressing of the succeeding key is prevented until the impulse characterized by the first key is sent out or a special warning signal comes into operation when a second key is operated too quickly. Further numerical senders possessing only one key board are known by whose keys stops are switched into the path of a cam so that a mechanical storing and an electrical transmission of the impulses to be sent out results. With this arrangement, however, the operation of the key strip is accordingly very much delayed.

Numerical senders are also known which permit a translating and correcting of the impulses sent out in an electrical manner with the help of the switching devices customary in telephone technique e. g., selectors. These devices, however, are expensive and also bulky owing to the use of switching means and the complex wiring necessitated by the arrangement.

The subject of the invention avoids the above mentioned disadvantages of the prior art in that through the transferring device the storing of the driving power for an independently running impulse sender is effected and also the choice of the stops limiting its path.

Mechanical impulse sending devices, so called impulse translators which transmit independently incoming impulses, have in themselves likewise already been suggested for installations, in which an impulse relay is operated by the influence of incoming impulses, and in which these incoming impulses are sent on corrected or strengthened. Through the combination of a single bank numerical sender and a mechanical translator with a mechanical impulse sending

device a predominantly mechanically working numerical sender is created whose construction is simple and economical of space, and which in view of its mechanical construction works with certainty and reliability, makes possible rapid operation of the set of keys and allows the impulse sent out to be in correct time independently of the speed of operating the key board, so that by a simple remodelling of the arrangement it is possible without anything further to send the impulse out converted. A further advantage is the small force with which the keys can be pressed in, since it is only the force of the restoring spring that has to be overcome.

15 In the following the subject of the invention is described and represented in the attached drawings.

Fig. 1 is a diagrammatic representation of the numerical sender in partial section.

20 Fig. 2 is a diagrammatic representation of the keyboard with its translating device.

Fig. 3 is a principal circuit for the arrangement of Fig. 1.

25 Fig. 4 is a further principal circuit for another constructional example of the numerical sender.

Fig. 5 is a diagrammatic partial representation of a further constructional example of the numerical sender.

30 Fig. 6 is a plan view of a portion of the structure shown in Fig. 5.

A key strip 1 (Figs. 1 and 2) possesses 10 keys 2 numbered 1-0, which are held in their rest position by a spring 3. In the operating path of each key 2, a lever 4 is arranged, which rotates about an axis 5. The lever 4 possesses an end portion 6 which yields in one direction. By pressing the key 2 the lever engages at its end 6 with a lever 7 and turns this about its axis. In the course of this movement the end 6 slips away from the edge of the lever 7 so that this immediately becomes free and travels back to its rest position under the influence of its spring 9. In this way, independent of the time for which the key 2 is depressed the lever 7 is operated only for a short time. When the key is released the lever 4 travels back to its rest position also under the influence of its spring 10, and the flapping end 6 can yield at the lever 7. By the operating of the lever 7 pins 11, which are provided to be movable in a disc 12, are actuated. Round the circumference of the disc 12 the pins 11 are so arranged that they have a separation from each other corresponding to the lever 7. In their existing set position they are held by friction, by way of example by a spiral spring gripping them

round. The disc 12 sits on an axle 13, which carries a toothed wheel 14, which engages with a cog 15 of a motor M. Furthermore, another toothed wheel 13' is fixed on the axle 13, and engages in a 1:1 ratio with a toothed wheel 16, which is arranged on a hollow shaft 17, which is supported in a bracket 18. On the hollow shaft there sits a movable bush or disc 19 cammed with it in the direction of rotation, which can be displaced by a clutch 20 which is controlled by a spring 22. The clutch 20 comes under the influence of an electromagnet 21. In the arrangement represented in Fig. 1 it is assumed that the magnet 21 is excited, so that the bush 19 is shoved as far as its left hand stop and in this arrangement presses to the left a pin 23 which acts on a lever 24 and displaces this in the clockwise direction against the restoring force of a spring 25. In this arrangement the lever 24 juts out onto the section of the movable pins 26. The movable pins 26 are circularly placed in the support 18 and equivalent in number to the pins 11, e. g., 4 x 10. When the magnet 21 is deenergized, the pin 23 under the influence of the spring effective over the lever 24 travels back and presses the bush as far as its right hand stop, since it would be freed by the clutch 20. In this way the lever 24 presses on one of the circularly arranged pins 26, which it stands directly opposite and pushes this to the left. The pin 26 so comes in the way of a pin 27, which is fixed in the turning disc 28. The turning disc 28 is controlled by a spiral spring 30, which is fastened to the disc 28 at one end and at its other end to a cup 31 for the spring, which is secured on the hollow shaft 17. A push-bar 32 extends through the hollow shaft 17 and stands with one of its ends in contact with an armature 33 of an electromagnet 34, whereby the armature 33 against spring 35 is influenced. The other end of the push-bar 32 works on a double armed lever 36, which is turnable about an axis 37, which is arranged in a pedestal bearing 38 on the disc 28. One end 39 of the lever 36 stands in contact with the peg 27 which is controlled by a spring 40. The disc 28 is constructed as a toothed wheel, which works together with a cog 41, which over a helical gearing 42 and a brake 43 regulates the running down of the disc 28.

A cog wheel 44 engaging with the disc 28 is joined to a cam 45, which works in an impulse contact 46, so that with the running down of the disc 28 the impulse impressed by the key 2 can be given out of this contact 46.

The arrangement works in the following way:

By a previous depression the peg 11 stands in its depressed condition opposite a contact nk and keeps this open. When now one of the keys 2 is depressed, one of the pegs 11 is displaced over the levers 4 and 7 and at the same time independently of the pressure of the key a contact anl is transitorily closed. Hence a current passes via earth, and relay 21, battery arrangement, so that the relay 21 is excited. The relay 21 brings the lever 24 out of reach of the circle of pins 26, so that the lever 24 connected with the hollow shaft 17 can be freely displaced. At the same time with the exciting of the relay 21 this closes its contacts 21' and 21''. Over earth, anl, 21', M, battery, the motor M is excited and begins to turn. The relay 21 holds after the operation of the contacts anl over battery 21, 21', ab, 21'', earth. With the commencement of the turning of the disc 12 the peg 11 still depressed from the preceding operation leaves its place so that the

contact nk is closed, so that henceforth the motor is kept switched in over earth, nk, M, battery. At the same time the contact ab is opened independently by the initial motion of the disc 12, so that after that, the motor M and the relay 21 holds, only dependent in addition on the contact nk. In the course of the rotation the pin 11 depressed in the preceding operation is put back into its initial position by a guide 47. The motor now keeps turning, until the next depressed peg 11 opens the contact nk and then the motor M as well as the relay 21 is switched off and at the same time the lever 24 is allowed to travel back to its initial position, under the influence of the spring 25, whereby the lever 24 pushes the pin 26, which through the turning of the hollow shaft 17 taking place at the same time stands opposite to the left and with that brings it within the reach of the pin 27. Over the pin 26 pushed to the left by the previous setting, the pin 27 touching it in this position, the push-bar 32 and the armature 33, the relay 34 is excited independently of the deexcitation of the relay 21, so that this relay, by means of its armature 33 pushes the push-bar 32 to the left in such a manner that the pin 27 is pressed to the right over the lever 39 and so pushes the pin 26 out of its path. The excitation of the relay 34 lasts only a short time, as will be explained more in detail presently, so that under the influence of the spring 40 the peg 27 travels back to its initial position, whereby the check for the disc 28 is lifted out of the way, and the disc now begins to rotate under the influence of the spring 30, which has been wound up by the displacement of the hollow shaft 17, until the peg 27 strikes on the next peg 26 which is pushed in its way. During this motion the cam 45 has operated the impulse contact 46 corresponding to the impressed key 2.

As is clear from the above, the sending out of the impulse over the contact 46 in a manner governed by the brake 43 results completely independently of the speed of pressing in the key 2 and the turning velocity of the characterizing device, namely the disc 12. Owing to this independence the velocity of the driving of the characterizing device by the motor M can be made as big as is desired, so that the easily operated keys can be operated very quickly one after the other i. e., the operations can follow one another practically without pause. By the quick turns of the disc 12 following one another a plurality of definite pegs 26 corresponding to the operated keys 2 are switched into the path of the pegs 27 by means of the lever 24 likewise taken with the motor over the hollow shaft 17, whereby the disc 28 slowly running down is switched from peg to peg, so that through the corresponding switching measure the relay 34 is excited each time for a short while after the contact of the peg 27 with one of the pushed in pegs 26 and in this way the further turning of the disc 28 in the manner previously described is effected, as far as the next displaced pin.

By the combination of a mechanical, independently rotating impulse sending device with a mechanical transferer driven in an unusual manner the numerical sender is not only simple and economical of space in its total construction but there is guaranteed a sure method of working of the numerical sender through the predominantly mechanical construction.

In the switching principal according to Fig. 4 the technical switching operations are more dis-

tinguished which in one working of the arrangement occur according to Fig. 1 in which, however, it is assumed that the release contact $an1$ influenced by the key 2 is not merely transiently closed but for as long as the key is depressed. Moreover, the switching on of the impulse sending disc 28 described above from pin to peg is effected by a particular contact breaker. If the release contact $an1$ is pressed for a long or short time the relay $An1$ is excited over earth, $an1, 10$ $An1, an2, an1$, battery and opens its contact $an1$, so that now the relay $An2$ is excited also, and with its contact $an2$ short circuits the relay $An1$. In this way the relay $An1$ is only excited for a short time independently of the duration of the operation of the contact $an1$. The relay $An1$ closes its contact $an1'$, which like the contact $an1$ in Fig. 3 excites the relay 21. Thereby the relay 21 closes its contact $21'$ and switches in the motor M over earth, $21', ab$. When the turning begins both lifter contacts $nk1$ and nk are closed independently of the motion of the disc 12. $nk1$ brings the relay Ab over earth, $nk1$, resistance, battery. The relay Ab opens its contact ab so that the motor now in dependence upon the contact nk remains switched on until this is opened under the influence of one of the depressed pins 11. The starting magnet 34 for the impulse sending disc 28 is operated by a circuit breaker U over earth, circuit breaker U, relay H, contact $h1$, relay 34 and thus, for example, the circuit breaker U sends out an impulse of 50 milli-seconds every 300 to 500 milli-seconds. Hence the relay H also energizes, and opens its contact $h1$ and so switches off relay 34 immediately and closes its contact $h2$, by which the second winding of the relay is excited over battery, resistance $h2$, HII, earth. Owing to this the relay H holds until the contact $26/27$ formed by the peg 27 on the one side and the peg 26 on the other is closed, i. e., until the disc 28 has reached the next depressed peg 26, upon which the winding HII is short-circuited over earth, HII, $26/27$, earth, and releases and so makes the circuit for the relay 34 controlled by the circuit breaker. By corresponding switching operations the switching further of the disc 28 by the last depressed peg 26 is prevented in a known manner.

In Fig. 5 a variation of the numerical sender according to Fig. 1 is shown, in which a translation of the characterized impulse results, for example, complementary impulses are given by this arrangement. If one therefore has characterized an impulse series of four impulses by pressing the key "4" then the arrangement of Fig. 5 gives out a series of six impulses. When by pressing a key 2 the motor M which drives the axle 13 over its toothed wheel 15 and the cog 14 and so also the cog 16 over the cog 15', is released the cog 16 carries a hollow axle with it. The magnet 21 is thus not yet excited, so that the clutch 20 frees the bush under the influence of the spring 22 which sleeve lies against its right-hand stop on the hollow shaft. The hollow shaft 48 and the hollow shaft 17 are separated from one another in this position, since a coupling 49 is provided which stands in connection with the clutch over the lever in such a manner that when the relay 21 is not excited the coupling 49 is separated from the hollow shaft 48. A switching member 51 is also carried by the hollow shaft 48 driven by the motor M, which member slides on contact segment 52 which is arranged on a disc 53. If for example, the key

"4" is depressed, a switching off of the motor is next effected over the contact nk , when the corresponding pin 11 is operated and at the same time a switching on of the relay 21 whereby over the sliding contact 51, 52 the circuit for the motor is made again independently of the contact nk . With the excitation of the magnet 21 the lever 24 is taken out of reach of the pin 26 in the pre-described manner and at the same time the coupling 49 is inserted, so that now the further turning of the motor causes a displacement of the lever 24 until the contact member 51 has released the segment 52 and so stopped the motor and deenergized the magnet 21. There results, as described, the pushing away of a peg 26, opposite to which is the lever 24. The segments 52 are thereby so arranged that the whole length excites 10 impulses, so that in a manner described above by the characterizing of the key for four impulses six complementary impulses are sent on. These, the coupling devices working the translator can also be used to translate incoming impulses with advantages, whereby instead of the motor M and the cog 15 a stepping switch controlled by the incoming impulses effects the cog 16. This type of translating preparation makes possible the use of numerical senders also in arrangements without the decadic system and/or the use of impulse transferring parts for coupling a system, which does not work with the decadic system. This coupling device is particularly simple with the construction of the numerical sender according to the invention, which is essentially characterized by the combination of a key strip and an unusually driven translating device with the impulse translator.

What is claimed is:

1. In combination, a sender for transmitting trains of impulses in accordance with markings applied thereto, a motor for driving said sender, a second motor, a key set for applying the markings to the sender, and means responsive to the actuation of any key for operating said second motor to store potential energy in said first motor.

2. A combination as claimed in claim 1, wherein in said second motor stores in said first motor different amounts of potential energy responsive to the actuation of different keys.

3. In combination, an impulse sender, two motors, a key set for applying one or more markings to said sender in rapid succession, means responsive to the actuation of any key for operating one of said motors to store potential energy in the other of said motors, said other motor thereafter effective to drive said sender at a predetermined rate regardless of the rapidity with which said sender is marked thereby to transmit one or more trains of impulses each dependent upon one of the markings applied to said sender.

4. In an impulse sender, a series of elements, a set of keys for controlling the marking off of any desired portion of the series, the portions corresponding to different keys containing different numbers of said elements, motor driven means thereafter associated with the elements of the marked-off portion in sequence and effective to control the transmission of impulses of a number dependent upon the number of elements in said portion, and means controlled by the actuation of any key to store driving power in the motor for said last means.

5. In combination, a key set, a register, means responsive to the actuation of any key for gen-

erating an impulse of predetermined maximum duration to initiate the operation of said register, discriminating means operated differently in dependence upon the key actuated and thereafter effective to control the register independently of said key to record a digit, a motor, means controlled by said register during the recording of said digit to store energy in said motor, and means operated by the energy stored in said motor to send impulses depending upon the digit recorded.

6. In an impulse sender, a pair of rotatable members, a clutch operable to link said members together, means operated one or more times in succession and effective upon each operation to rotate one of the members through a predetermined angle, means for rendering said clutch effective after said one member has rotated through any desired amount of said predetermined angle thereby to cause the other member to be driven by said one member only during the remainder of that rotation of said one member, and means controlled by said other member to send one or more groups of impulses each depending upon the angle through which said other member is moved during a rotation of said one member.

7. In a digit registering device, a plurality of

keys each having assigned to it a digital value, a member moved through a predetermined number of positions responsive to the actuation of any key regardless of the digital value assigned to that key, a second member normally disengaged from the first member but adapted to be driven by the first member when linked thereto, means controlled in accordance with the digital value of the actuated key to link said second member to the first member after said first member has moved through a certain number of said predetermined number of positions, said certain number depending upon the digital value of the actuated key, and means controlled by the movement of the second member to register a digit.

8. In combination, a sender for transmitting trains of impulses in accordance with markings applied thereto, a motor for driving said sender, a key set for applying markings to the sender, means responsive to the actuation of any key for storing energy in said motor, said means controlled at times by the actuation of two of said keys in succession to accumulate in said motor a greater amount of energy than could be stored therein by actuation of either one of said two keys alone.

GEORG ZAFF.
